UNITED STATES PATENT OFFICE.

MICHAEL BULKA, OF GARDNER, MASSACHUSETTS, ASSIGNOR, BY DIRECT AND MESNE ASSIGNMENTS, TO ASTRONOMICAL CLOCK MANUFACTURING COMPANY, OF CHICAGO, ILLINOIS, A CORPORATION.

ASTRONOMICAL CLOCK.

1,416,605.

Specification of Letters Patent. Patented May 16, 1922.

Application filed December 1, 1919. Serial No. 341,585.

To all whom it may concern:

Be it known that I, MICHAEL BULKA, a citizen of the United States, residing at Gardner, in the county of Worcester and State of Massachusetts, have invented new and useful Improvements in Astronomical Clocks, of which the following is a specification.

The object of my present invention is the provision of an improved clock for exemplifying and illustrating the movements of the earth and moon about the sun, and the movement of the moon in its orbit about the earth, and these movements in concert with the actual happenings and so as to typify the four seasons of a year.

To the attainment of the foregoing, the invention consists in the improvement as hereinafter described and definitely claimed.

20 In the accompanying drawings—

Figure 1 is a front elevation showing the best practical embodiment of my invention that I have as yet devised.

Figure 2 is a detail front elevation illustrating the twenty-four hour hand and the year hand in proper relation to the dial complementary to said hands.

Figure 3 is an enlarged vertical section taken in the plane at right angles to Figure 1, and showing the mechanism of the clock.

Figure 4 is a detail section taken in the plane at right angles to Figure 3 and showing the driving connections complementary 35 to the earth and the moon.

Figure 5 is a detail section through the dial and the parts adjacent thereto.

Similar numerals and letters of reference 40 designate corresponding parts in all of the views of the drawings.

The clock casing 1 is preferably, though not necessarily, of the configuration illustrated, and it carries at 2 an ordinary clock dial, and at 3 a calendar dial; the calendar dial in the illustrated embodiment being disposed above the clock dial 2.

Extending through the upper wall of the casing 1 is a vertical fixed shaft or rod 4 on which is a representation 5 of the sun, and 50 arranged alongside the sun is a representation 6 of the earth, and a representation 7 of the moon. These three representations may be and preferably are embellished with a view to illustrating their respective sub-

jects and at the same time enhancing the 55 finished appearance of the clock.

The dial 3 is provided with an inner annular portion 8, divided into segments bearing the inscriptions "Spring," "Summer," "Autumn," "Winter." Said dial 3 is also 60 provided with an outer annular portion 9 bearing the names of the months arranged in regular sequence. Surrounding the outer dial portion 9 is a revolute annulus 10 on which are twenty-four divisions numbered 65 from 1 to 12, in two series. The said revolute annulus is turned through a complete revolution once in 365 days, and is designed to be driven by the year hand, hereinafter referred to. One-half of the revolute annulus 10 is darkened from a graduation VI to 70 an adjacent graduation VI, with a view to indicating the hours of darkness. The remainder or undarkened portion of the annulus 10 is designed to indicate the daylight 75 hours.

Movable in front of the dial 2 are the ordinary hour hand 11 and minute hand 12, and movable in front of the dial 3 are two hands, one of which, 13, I denominate the 80 twenty-four hour hand, and the other, 14, I denominate the year hand.

The moon 7 is carried on an arm 15 having a center of movement below the center of the earth 6, so as to permit of the moon 85 being moved in an orbit about the earth. The earth 6 is arranged with its axis disposed at an angle to the perpendicular in conventional manner and is mounted in an annular frame 16. Coincident with the axis of the 90 earth is a shaft 17 on which is a spur gear 18.

The framework illustrated may be of the construction shown, or of any other construction compatible with the purpose of 95 my invention, and in the lower portion of said framework is arranged ordinary clock-work indicated by B. Journaled in the framework is an arbor E driven from the main clock-work and designed to be turned 100 through four revolutions in twenty-four hours. The said arbor E carries a gear e intermeshed with a gear f on an arbor F, and designed to rotate the latter. The gear f drives a gear g on an arbor G, and said 105 gear g serves to effect the motion of the twenty-four hour hand 13. Said gear g drives a smaller gear h on the arbor H which

carries a gear *i* which meshes with a gear *j*. The gear *j* is movably secured to a gear *k*, and the gear *k* is mounted on an arbor I to rotate a gear *l* and drive a shaft *J*, which 5 shaft *J* is designed to make 366 revolutions in 365 days, and carries the twenty-four hour hand 13. The function of this hand 13 is to illustrate the rotation of the earth about its axis. The hand 13 is designed to make 10 one and 1/365 revolutions in twenty-four hours, or 366 revolutions in 365 days, and in order to compensate for the fraction so that the hour hand will indicate the correct time, the revoluble annulus 10 is provided; said 15 annulus 10 being operable by the year hand 14, and designed to be turned through a complete revolution once in 365 days, or through 1/365 of a revolution in every twenty-four hours. The shaft *J* carries a gear *m*, and 20 meshed with the gear *m* is a gear *n* loosely mounted on a stud 23. The said gear *n* is intermeshed with a gear *o* carried by an arbor *K*. Said arbor *K* also carries a gear *p* that is intermeshed with a gear *q*, mounted 25 on an arbor *L*. Said arbor *L* also carries a gear *r* that is intermeshed with a gear *s* movably secured to a sleeve *M*, designed to turn loosely on the arbor or shaft *J*. The said sleeve *M* carries the year hand 14, designed 30 in combination with the dial 3 to show the rotation of the earth around the sun. Said arbor *J* also carries a miter gear *t* which is intermeshed with a miter gear *u* on a vertical sleeve *N*, which sleeve *N* is adapted to 35 turn about the shaft 4. At its upper end the sleeve *N* carries a miter gear *v* which is intermeshed with a miter gear *w* on a horizontal sleeve *O*. At the outer end of the sleeve *O* is carried a miter gear *x*, and this 40 miter gear *x* is intermeshed with a miter gear *y* on the lower end of an upright sleeve *P*. This sleeve *P* is designed to turn loosely about an arbor *Y*, and is provided at its upper end with a spur gear *z* intermeshed 45 with a gear *Q* which is supported on the frame 16 and is intermeshed with the gear 18 on the shaft 17 so as to rotate the earth 6 about its axis once in twenty-four hours. At its lower end the sleeve *P* carries a miter 50 gear *y* and a spur gear *a'*; said gear *a'* being intermeshed with a spur gear *S*, and the said gear *S* being loosely mounted on a stud fixed with respect to the sleeve *d'*. On the said stud is carried a gear *b'* which is intermeshed 55 with and designed to drive a gear *c'* fixed to a sleeve *T* which loosely surrounds the sleeve *P*. On the said sleeve *T* is the arm 15. The

sleeve *M* carries a miter gear *y'* in mesh with a miter gear *g'* on the lower end of an upright sleeve *U*, and this sleeve *U* carries a horizontally extending sleeve *V* to which latter is fastened the sleeve *d'* receiving the rod *Y*, which rod carries the frame 16. A miter gear *h'* is fixed to the shaft 4. The sleeve *V* surrounds the sleeve *O*, and said sleeve *O*, in turn, surrounds a shaft *W* having a miter gear *z'* at its inner end, and a miter gear *j'* at its outer end. The gear *j'* being intermeshed with the gear *h'*, and the gear *z'* being intermeshed with the gear *h'*. 70 Manifestly the sleeve *V*, swinging around the sun, brings about rotation of the gear *z'* and driving of the parts connected with said gear *z'*. By virtue of the gear *j'* and *h'* being intermeshed, the frame 16 is always held in 75 the same position with a view to illustrating the four seasons of the year.

The shaft or rod 4 on which the sun 5 is carried is fixed at 5^a with respect to the framework. 80

The manner in which the annulus 10 is driven by the year hand 14 will be understood when it is stated that the said annulus 10 is provided with a small wire clamp 10^a into which the year hand 14 is fitted, Fig. 5. 85 Consequently as the hand 14 makes a complete revolution once in 365 days, the annulus 10 makes the same revolution in the same time.

It will be apparent from the foregoing 90 that notwithstanding its capacity of function as hereinbefore set forth, my novel clock is simple and inexpensive in construction, and is not liable to get out of order after a short period of use. It will also be apparent 95 that the clock, in addition to its educational value, is adapted to form an ornamental object in a class-room.

Having described my invention, what I claim and desire to secure by Letters-Patent, 100 is:

In an astronomical clock, a year hand, a twenty-four hour hand, clock mechanism for rotating said hands, a dial, and a revoluble annulus associated with the dial and having 105 means engaged by the year hand for the movement of the annulus by said hand, said annulus bearing on its face figures representative of the hours in a day and arranged in two series of one to twelve each in regular 110 sequence.

In testimony whereof I affix my signature.

MICHAEL BULKA.
